LOCK.

1,235,616.

Specification of Letters Patent.

Patented Aug. 7, 1917.

Application filed March 1, 1916. Serial No. 81,457.

To all whom it may concern:

Be it known that I, HENRY G. VOIGHT, a citizen of the United States, residing in New Britain, county of Hartford, and State 5 of Connecticut, have invented certain new and useful Improvements in Locks, of which the following is a full, clear, and exact description.

This invention relates to locks, and more 10 particularly to a door lock comprising a latch bolt which can be dogged or deadlocked in protracted position by means of a thumb turn or similar instrumentality at the inside of the door, so as not to be retractable 15 by the change key from the outside of the door, although it can be retracted by the emergency key. The invention also relates more especially to a lock in which a pin tumbler mechanism when actuated by one 20 key will shift the dogging device out of operative position, and also retract the latch, whereas another key for the pin tumbler mechanism can retract the latch when it is free but cannot actuate or control the dog- 25 ging mechanism.

The objects of the invention are to provide improved mechanism for carrying out the functions above stated; to furnish a lock 30 in which a single rollback mounted on a pin tumbler cylinder is adapted to be actuated by one key so as to cause the dogging means to be moved into or withdrawn from the operative position, and the latch bolt to be retracted, whereas said rollback is operable 35 by another key only to the extent of retracting the bolt when the dogging means is in the inoperative position; and to improve and simplify the general construction and 40 operation of devices of the class to which the invention relates.

To these and other ends, the invention consists in the novel features and combinations of parts to be hereinafter described and claimed.

45 In the accompanying drawings,

Figure 1 is a front elevation of a lock embodying my improvements with the cap plate removed, showing the dogging slide for the latch bolt in the inoperative position, the operative position of said slide being indicated in dotted lines;

Fig. 2 is a view of the upper part of the lock, showing the latch bolt retracted by the change key;

Fig. 3 shows the latch bolt dogged by the 55 dogging slide and the rollback on the cylinder commencing the operation of withdrawing the dogging slide and retracting the bolt;

Fig. 4 is a fragmentary view, showing the 60 completion of the operation just mentioned;

Fig. 5 is a section on line 5—5 of Fig. 1, showing the change key inserted into the cylinder;

Fig. 6 is a section on line 5—5, but looking in the opposite direction, showing the 65 emergency key inserted into the cylinder;

Fig. 7 is a detail section on line 7—7 of 70 Fig. 2, illustrating the operation of the change key;

Fig. 7^A is a detail section on line 7^A—7^A of Fig. 3, showing the operation of the 75 emergency key;

Fig. 8 is a section on line 8—8 of Fig. 1;

Fig. 9 is a section on line 9—9 of Fig. 1; 75 and

Fig. 10 is a detail edge view of the dog- 80 ging slide.

In the particular form shown, the case 11 of the lock, having the usual face plate 12, 80 contains a latch bolt 13 normally projected by a spring 14. The stem 15 of the bolt carries a head 16, engaged by a yoke 17 adapted to be actuated by an inside hub 18 and an outside hub 19. By this means, the 85 latch bolt may be retracted by the inside and outside knobs, and usually the outside knob may be dogged by stop work mechanism 20, 21, 22, associated with the outside hub 19 in the usual manner, although this 90 is not a material feature of the invention.

The latch bolt 13 may be retracted from the outside of the door through a cylinder lock 23, adapted to actuate an elbow lever 24, pivoted to the case at 25, and having 95 a depending arm 26 engaging the cross-head 16 of the latch bolt and a portion of the yoke 17 in the usual manner. The other arm 27 of the elbow lever 24 is adapted to be depressed by a bit, dog or rollback 100 28 of the cylinder lock 23, whereby the arm 26 of the elbow lever 24 is carried rearwardly to retract the latch bolt.

The latch bolt 13 is adapted to be dogged or deadlocked in its protracted position by 105 means of a thumb turn or the like at the inside of the door. In the embodiment illustrated, a thumb turn hub 29 is mount-

ed for oscillatory movement between the walls of the case. Projecting from the thumb turn hub 29 is an arm or wing 30 adapted to move in a vertical direction a 5 slide 31, suitably guided in the case at right angles to the latch bolt, and having a projection 31^a at its lower part adapted to extend into the path of the cross-head 16 and thereby block the incursion of the bolt. In 10 the form shown, the arm 30 of the thumb turn hub fits between pins or abutments 32, 33 projecting from the dogging slide 31 so that if the arm 30 is moved downward it will abut the pin 33 and thereby move 15 the slide to dogging position with respect to the latch bolt, whereas if the arm is moved upward, it will abut the pin 32 and thereby move the slide upwardly so as to release the latch bolt. This slide 31 is guided 20 in the case by means of suitable lugs which it is not necessary to describe in detail, and when once moved to a predetermined position it tends to retain that position by virtue of the frictional engagement 25 of a spring 34 (socketed in the pin or projection 33) with the cap plate of the case. In order to actuate the slide 31 by means 30 of one of the keys for the cylinder lock 23, as hereinafter described, the upper end portion of the slide is provided with a lateral projection 35 adapted to be engaged by the operating projection 28^a of rollback 28, for the purpose of depressing the slide into the dogging position shown in Fig. 3. For the 35 purpose of raising the dogging slide out of the operative position by means of said key, as hereinafter described, a slide-actuating member 36 is provided. This preferably takes the form of a lever or walking beam, pivoted intermediate of its ends on a pin 37 which is socketed in the back of the case, and which engages a hub or bearing portion 38 on the under surface of lever 36, as shown in Fig. 6. One extremity 40 45 39 of the lever 36 is disposed between the pin 32 and the abutment or projection 35 on the upper end of the slide and is adapted to raise the slide by engaging said abutment. The opposite end of the lever 36 50 has a lip 40 extending rearwardly therefrom at the upper edge and overlying a shoulder 41 on the extremity of arm 27 of the latch retracting lever. When the rollback 28 rotates in the plane which it occupies in Fig. 5, it is adapted to actuate the latch retracting lever through a small lever 42, pivoted on a post 43, and having its free end supported and resting on a shoulder 44 on the free extremity of arm 27. In 55 withdrawing the latch, the operating projection 28^a of the rollback abuts against the free end 42^a of lever 42 and presses it down on the free end of arm 27 so as to actuate the lever 24 to retract the latch, as 60 shown in Fig. 2. The rollback 28 may, 65

however, be displaced rearwardly so as to rotate in another plane, as hereinafter described, and when so rotated it is adapted to engage the free end 45^a of a lever 45, pivoted on the post 43 in front of the lever 42. The end portion 45^a of lever 45 rests freely on the rearwardly turned lip 40 of the walking beam or lever 36, and thus when the lever 45 is depressed by the abutment of the operating projection of the 75 rollback with its end portion 45^a (Fig. 4), the adjacent end of lever 36 is depressed, and in turn it depresses the arm 27 of lever 24 to retract the latch bolt, while at the same time the opposite end portion 39 80 of lever 36 is raised to move the slide 31 out of the path of the latch bolt by engagement of the portion 39 with the under surface of the projection 35, as shown in Fig. 4.

Referring now to the detailed construction of the cylinder lock 23, it will be observed that this cylinder lock has the usual case 46, face plate or escutcheon 47, and key plug or barrel 48. The dog or rollback 28 is secured on the rear end of the key plug 48. Preferably it embraces an extension on the rear end of the key plug, and is secured to said plug by suitable screws 48^a, as shown. Surrounding the key plug is a sleeve 49 rotatable concentrically with respect to said key plug, and sectional pin tumblers 50 of the usual type connect the key plug, sleeve and casing, the arrangement being such that one key is adapted to rotate the key plug individually, while another key rotates both the key plug and sleeve. When the change key 51 is used to actuate the cylinder lock, the rollback 28 will be rotated in its normal plane, so that its operating projection 28^a will turn in the plane of the operating projection or end portion 42^a of lever 42, and thereby depress the arm 27 of the latch retracting lever and retract the latch bolt without actuating the lever or walking beam 36. When the emergency key 52 is used to actuate the cylinder lock, the operating projection of the rollback will be rotated in the plane of the operating projection 45^a of the secondary lever 45, so as to operate the lever 36 to withdraw the dogging slide from the operative position, in case it occupies that position. To accomplish these results, the sleeve 49 is movable endwise of the casing 46 when the emergency key is used, and to permit this the shoulder 53 at the forward end of the sleeve 49 operates in a somewhat wider rabbet 54 in the face plate of the cylinder, so that when the sleeve is released and turned by a key, as shown in Fig. 3, the sleeve may move rearwardly until the shoulder 53 takes up against a shoulder 55 on the casing of the cylinder. In other words, the shouldered portion of the casing at the face of the cylinder, which limits the endwise movement of the sleeve, is farther back 100 105 110 115 120 125 130

than in ordinary cylinders so that the sleeve may have an appreciable rearward movement. In this operation, the sleeve is locked by the pin tumblers 50 to the key plug 48, 5 so that the latter is likewise carried rearwardly, together with the rollback 28, and therefore instead of rotating in the normal plane of rotation, the rollback is carried rearwardly and rotated in the plane of the lever 45, which actuates the lever 36. Before the sleeve is turned on its axis, it should be held against rearward movement by suitable means other than the pin tumblers. To this end, I prefer to attach to the rear of the 10 cylinder lock a plate 56, having a depending tongue or lip 58 abutting against the rear face of a cam member 59, screwed or otherwise secured to the rear extremity of the sleeve 49. When the emergency key is inserted into the cylinder, the engagement between the lip 58 and cam 59 will take up rearward thrust on the sleeve and thereby relieve the tumblers of strain and wear; but when the sleeve is turned by the emergency 15 key, the cam 59 will disengage the lip 58 and thereby permit the sleeve to be thrust rearwardly under the usual pressure on the key, so that the rollback 28 will be rearwardly displaced, as above explained. By preference, the cam 59 is screwed against the rear face of the sleeve, and that part of the cam which engages the lip 58 is in the form of a radial projection which is rounded off at its rear face, while the coöperating lip 58 is 20 rounded off at the front face. In Fig. 5, I have shown the position of the parts when the change key is inserted into the cylinder. This key is only operative to retract the latch bolt through the levers 42, 24, as previously explained. When the emergency key 25 is inserted in the cylinder, as shown in Fig. 6, the pin tumblers are racked so as to permit the key plug and sleeve to rotate together, and as the sleeve moves backwardly, the key plug and its rollback are carried 30 thereby. When the key is inserted, rearward movement of the rollback is at first prevented by the engagement of lip 58 with cam 59, but when the key is turned in either direction, the 35 projection of the cam passes clear of the lip, and is then moved rearwardly by the usual pressure of the hand of the person actuating the lock, so as to carry the rollback into the plane of the arm 45 and lever 36. If, however, the pressure on the key is not sufficient 40 to move the rollback to its rearmost position, this will be effected by the cam action of the cam 59 on the casing of the cylinder lock which is cut away to present cam surfaces 45 adapted to be contacted by the cam 59, as the latter is rotated in one or the other direction, and to thrust the rollback in a rearward direction. The cam rotates in contact with the rear face of the cylinder casing, after said cam has been thrust rearwardly, and therefore it will be understood 50 that the cam or key thrusts back the rollback when said key has been turned to a very slight extent, and that thereafter the rollback is prevented from moving out of the plane of the arm 45 and lever 36 until the key is turned back to its initial position. As the parts approach the initial position, the cam 59 is thrust against the lip 58, which is also in the nature of a cam, and said lip thrusts the cam forwardly again so that when the tumblers are lined up for the removal of the key, the sleeve, key plug and rollback will occupy the normal positions relatively to the cylinder. 55

Supposing that the improved lock is used on the door of a hotel room, and the guest wishes to lock the door against intrusion. To do this, the thumb turn is rotated by the usual thumb knob in a clockwise direction, so as to move the dogging slide down into the operative position, as shown by the dotted lines in Fig. 1. Under these conditions, the door cannot be released from the outside by the change key or any other key which rotates the rollback 28 in its normal plane of rotation. Access to the room can still be had, however, by the use of the emergency key which carries the rollback 60 into the plane of lever 45, so as to withdraw the dogging slide from operative position by pressing down the left hand end of lever 36 through the lever 45, at the same time that the lever 45 operates the lever 24 to retract the latch bolt. The arrangement is such that the latch bolt is retracted and the dogging slide is raised, as the rollback 28 moves from the position shown in Fig. 3 to that shown in Fig. 4. In other words, a very slight rotation of the rollback will 65 accomplish these two results. The latch bolt and the slide move together, but the slide keeps ahead of the latch bolt, so to speak, so as not to block the latch bolt at any point and thereby permit a free retraction of the 70 bolt. 75

The emergency key or another key which will displace the rollback in a rearward direction may also be used as a shut-out key, so that the door when locked by such key 80 cannot be released by another key or keys. In the particular form shown, the emergency key will serve as a shut-out key because it will actuate the rollback to depress the dogging slide into the operative position. 85 When it is desired to lock the door against the keys of lower order, the emergency key is inserted into the cylinder lock and rotated in a clockwise direction with respect to Fig. 3, so that the operating projection of the 90 rollback is moved into engagement with the abutment or projection 35 on the upper end portion of the slide, as indicated in dotted lines in Fig. 3, whereby the slide is moved down into a position to block the incursion 95 of the key. 100

of the bolt. The door can still be opened by the emergency key, however, for when the same is turned in a counterclockwise direction with respect to Fig. 3, the walking beam or lever 36 will be actuated to raise the slide concurrently with the withdrawal of the bolt, as previously described. It is understood, of course, that the change key and other keys which rotate the key plug individually cannot at any time actuate the dogging slide, because the operating projection 35 of said slide is located out of the normal plane of rotation of the rollback, and will only engage the rollback when the same has been displaced in a rearward direction.

Various changes in the details of the construction may be adopted without departing from the scope of the invention as defined in the claims. Naturally in giving a complete description of the particular embodiment selected for illustration, I have had to describe a number of features which are immaterial to the broad principles involved.

I do not claim herein the cylinder lock *per se* having a rearwardly displaceable rollback, as claimed in my application Serial No. 74,461; nor do I claim broadly herein the combination with mortise lock mechanism having two members lying in different planes, of a cylinder lock having a rollback to engage and operate either of said members, as claimed in my application Serial No. 74,460; neither do I claim broadly herein the combination of a latch bolt, retracting mechanism therefor, dogging mechanism therefor, a cylinder lock having a rollback, a key for said cylinder lock adapted to operate said retracting mechanism alone through said rollback, and another key for said cylinder lock adapted to operate both said retracting mechanism and said dogging mechanism through said rollback, as claimed in my application Serial No. 79,717.

What I claim is:—

1. In a lock, a latch bolt, retracting mechanism therefor, mechanism operable from the inside of the room for dogging said latch bolt in its protracted position, a cylinder lock, and a single rollback on said cylinder lock arranged relatively to said mechanism for operating said dogging mechanism to release the bolt, and for engaging and operating said retracting mechanism to retract the bolt as said rollback moves in the same direction; substantially as described.

2. In a lock, a latch bolt, retracting mechanism therefor, mechanism for dogging said bolt in protracted position, a cylinder lock, a rollback for said cylinder lock, a key for said cylinder lock adapted to operate said retracting mechanism alone through said rollback, and another key for said cylinder lock adapted to release said dogging mechanism through said rollback concurrently

with the operation of said retracting mechanism by the latter; substantially as described.

3. In a lock, a case having a face plate, a latch bolt in said case, retracting mechanism for said latch bolt, mechanism for dogging said latch bolt in its protracted position, a cylinder lock, and a single rollback on said cylinder lock arranged for releasing said dogging mechanism and for engaging and operating said retracting mechanism to withdraw the bolt as said rollback is turned slightly from its normal position toward the face plate, said rollback operable when turned in the opposite direction to move said dogging mechanism into the operative position; substantially as described.

4. In a lock, a latch bolt, mechanism for dogging said latch bolt in its protracted position, thumb turn means for moving said dogging mechanism into its operative position from the inside of the room, a separate means for moving said mechanism into its inoperative position, a cylinder lock, and a rotary rollback on said cylinder lock arranged and located for operating said last-named means to release the bolt, and for retracting the bolt, as said rollback moves in the same direction; substantially as described.

5. In a lock, a latch bolt, retracting mechanism therefor, a slide for dogging said latch bolt in its protracted position, a thumb turn member for moving said slide into its operative position, a member separate from said thumb turn member for moving said slide into its inoperative position, a cylinder lock, and a rollback on said cylinder lock for operating said last-named member to release the bolt, and for engaging and operating said retracting mechanism concurrently with the withdrawal of said slide; substantially as described.

6. In a lock, a latch bolt, a retracting lever therefor, a slide for dogging the bolt in protracted position, a thumb turn member for operating said slide, an operator in the case for moving said slide to the inoperative position, a cylinder lock, a rollback for said cylinder lock, a key for said cylinder lock adapted to actuate said retracting lever alone through said rollback, and another key for said cylinder lock adapted to move said rollback into operating relation to said slide operator and said retracting lever on one and the same movement of said rollback so as to withdraw the slide and retract the latch bolt concurrently; substantially as described.

7. In a lock, a latch bolt, a member for dogging said bolt in its protracted position, retracting means for said bolt, thumb turn means for moving said dogging member into its operative position, means for moving said dogging member into an inoperative position, a cylinder lock, and a single roll-

back for said cylinder lock arranged and located to actuate said last-named means and said retracting means at the same time, said rollback also operable to move said dogging member into dogging position; substantially as described.

8. The combination with a latch bolt mechanism having a retracting lever and a dogging slide lying in different planes, of a cylinder lock having a rollback to engage and operate either said retracting lever or said dogging slide; substantially as described.

9. The combination with a latch bolt mechanism having a retracting lever and a dogging slide, of a cylinder lock having a rearwardly movable rollback adapted to engage and operate either said retracting lever or said dogging slide; substantially as described.

10. In a lock, a latch bolt, a retracting member therefor, a slide for dogging said bolt in retracted position, a cylinder lock, a rollback for said cylinder lock, a key for said cylinder lock adapted to move said rollback into engagement with said retracting member, and another key for said cylinder lock adapted to move said rollback into another plane so that it will engage said dogging slide; substantially as described.

11. In a lock, the combination with a case, a latch bolt therein, a deadlocking slide movable at right angles to the latch bolt, a cylinder lock carried by the case and having a rollback, a latch retracting lever pivoted to the case and adapted to be actuated by said rollback, a key for operating said lever to retract the latch bolt when said slide is in the inoperative position, a second key for moving said rollback into engagement with said slide so as to shift the latter into operative position, and means for moving the slide out of its operative position when said rollback is turned in the opposite direction to retract the bolt by means of said second key; substantially as described.

12. In a lock, a latch bolt, a deadlocking slide movable at right angles thereto, a retracting lever for said latch bolt, a cylinder lock having a rollback, a key for actuating said rollback to operate said retracting lever and withdraw the bolt, means for moving said slide into deadlocking position, a second key for moving the deadlocking slide into operative position by means of said rollback, and means for moving the deadlocking slide out of operative position through said rollback while the latch bolt is being retracted thereby; substantially as described.

13. In a lock, a latch bolt, a deadlocking slide movable at right angles thereto, a retracting lever for said latch bolt, a cylinder lock having a rollback, a key for actuating said rollback to operate said retracting lever and withdraw the bolt, means for moving

said slide into deadlocking position, a second key for moving the deadlocking slide into operative position by means of said rollback, and a lever pivoted intermediate of its ends and adapted to be operated by said rollback when the latter is actuated by said second key, for moving the slide out of operative position as the latch bolt is retracted; substantially as described.

14. In a lock, the combination of a case, a latch bolt therein, a deadlocking slide movable at right angles to the latch bolt, a thumb turn hub for moving said slide into and out of deadlocking position with respect to the latch bolt, a retracting lever for the bolt, a cylinder lock out of line with said thumb turn hub and having a rearwardly movable rollback located in the space between said deadlocking slide and the free end of said retracting lever, a key for turning said rollback in one plane to operate said retracting lever and withdraw the bolt, another key for turning said rollback in another plane, and a walking beam member engaging the free end of the retracting lever and a part of the deadlocking slide so as to withdraw said slide from operative position by means of said second key concurrently with the retraction of the bolt; substantially as described.

15. In a lock, a case, a latch bolt therein, a deadlocking slide movable at right angles to the latch bolt, a latch retracting lever pivoted to the case, a swinging walking beam member pivoted intermediate of its ends and having one end arranged to engage said deadlocking slide and move it out of operative position, the other end of said walking beam member being in proximity to one end of said latch retracting lever, two keys, and a cylinder lock mechanism adapted to actuate said walking beam member and said latch retracting lever when operated by one key, said cylinder lock mechanism inoperative on said walking beam member when the other key is used; substantially as described.

16. In a lock, a case, a latch bolt therein, a slide for deadlocking the latch bolt, a swinging walking beam member pivoted intermediate of its ends and having one end operatively associated with said deadlocking slide to shift the same, and a cylinder lock mechanism to actuate said walking beam member from the opposite end thereof; substantially as described.

17. In a lock, a case, a latch bolt therein, a slide for deadlocking said bolt, a lever for retracting said bolt, a swinging member pivoted to the case intermediate of the ends of said member, and having one end associated with said slide to actuate the same, the other end of said member being operatively associated with said lever to actuate the same, and means for operating said member; substantially as described.

18. In a lock, a case, a latch bolt therein, a deadlocking slide movable at right angles to the latch bolt, a latch retracting lever pivoted to the case, a swinging member having one part arranged to engage and operate said deadlocking slide, and having another part arranged to engage and operate said latch retracting lever, two keys, and a cylinder lock mechanism adapted to actuate said lever and said slide by means of said member when one of said keys is used, said cylinder lock mechanism being operative on said lever only, when the other key is used; substantially as described.

19. In a lock, a case, a latch bolt therein, a slide for deadlocking the latch bolt, a lever for retracting the latch bolt, a single member in the case for operating both said lever and said slide, key mechanism, a key for actuating said key mechanism to operate both the lever and slide by means of said member, and another key which actuates said key mechanism to operate said lever independently of said operating member; substantially as described.

In witness whereof, I have hereunto set my hand on the 28th day of February, 1916.

HENRY G. VOIGHT.
